HARVEY B. RICHARDS, OF BAY CITY, TEXAS.

IGNITION SYSTEM FOR INTERNAL-COMBUSTION ENGINES.

1,264,130.

Specification of Letters Patent. Patented Apr. 23, 1918.

Application filed March 27, 1917. Serial No. 157,766.

To all whom it may concern:

Be it known that I, HARVEY B. RICHARDS, a citizen of the United States, residing at Bay City, in the county of Matagorda and

5 State of Texas, have invented new and useful Improvements in Ignition Systems for Internal-Combustion Engines, of which the following is a specification.

This invention relates to ignition systems 10 for internal combustion engines and comprehends the provision of a dual ignition system for multiple cylinder engines with which either battery or magneto current may be used and having only two coils, one 15 with a vibrator for the magneto current and one without a vibrator for the battery current. The high tension or secondary wire from both coils being connected to one insulated wire leading to a high tension distributor, which distributes the high tension or secondary current to terminals of insulated wires leading to the spark plugs.

One of the objects of the invention is to provide in a system of this nature a timing 25 device which will give absolutely accurate timing of the ignition in all cylinders, since the primary circuit is made and broken for each of the spark plugs by the same interrupter, operated by a single cam, thus assuring the firing of each cylinder at the same 30 point of its piston travel, and preventing some cylinders firing too early and others too late as is now the case with other timing devices which employ separate mechanism for making and breaking the circuit for each spark plug.

Another object of the invention is to provide a system which will work equally well 40 on either battery or magneto circuit by simply throwing a switch to whichever circuit is desired.

Another object is to provide a system of this nature having maximum economy in the consumption of current, such end being 45 attained by having the contact on the battery circuit practically instantaneous and the contact on the magneto circuit adjustable to the most economical and efficient duration.

50 The invention also aims to generally improve devices of this nature to render them more practical, useful, and commercially desirable.

With these and other objects in view as 55 will become more apparent as the description proceeds, the invention consists in cer-

tain novel features of construction, combination and arrangement of parts as will be hereinafter fully described, illustrated and claimed.

60

In the drawings,

Figure 1 is a plan view of the apparatus with the casing removed and the bridge broken away.

Fig. 2 is a top plan view of the entire 65 apparatus.

Fig. 3 is a vertical sectional view through the timer.

Referring in detail to the drawings by numerals, 1 designates an auxiliary shaft which 70 may be driven by the engine in any manner and which is secured at its upper end to a shaft 7. The shaft 7 is formed with a socket in its lower end into which the auxiliary shaft 1 projects. A set screw 8 or other suitable fastening means locks the two shafts together. The shaft 7 may be connected direct to the engine if desired.

The shaft 7 is of a reduced diameter 80 throughout part of its length as indicated at 9 and the inner end of the reduced portion is threaded for engagement with a beveled ring gear 10 as shown and a lock nut 11 secures the gear firmly on the shaft in engagement with the shoulder formed by the 85 inner end of the unreduced lower portion thereof.

A bushing 12 of suitable material encircles the shaft 7 and is provided at its inner end with a circular flange 13 which forms 90 a bearing for the gear 10.

A shell or housing 14 surrounds the gear 10 and is provided with a neck 15 which receives the bushing 12. The interior of the housing is suitably recessed as at 16 to accommodate the bushing flange 13. A collar 17 is secured to the shaft 7 by a lock screw 18 and serves to hold the shell 14 properly positioned. A washer 19 is interposed between the bushing and the collar 17 to prevent 100 an escape of lubricant. A two piece cover 20 having the half sections 21 and 22 is mounted on the top of the shell 14 and forms a support for parts to be hereinafter described.

105 A beveled gear 23 meshes with the ring gear 10 and is formed integrally on a tubular shaft or sleeve 24 which extends through the cover 20 and which is formed integrally on its upper end with a cam 25. 110 The gear is secured to a bridge 26 by a bolt 27 and nut 28. The bridge has its central

portion spaced from the cover and is secured in position by a plurality of screws 29 which extend therethrough and through the cover into the shell 14.

- 5 Insulated terminal screws 30 and 31 assist in securing the cover in position and these screws support, respectively, the arms 32 and 33. The arm 32 is provided with an adjustable contact screw 34 working through 10 an ear 35, and the arm 33 is provided with an adjustable contact screw 36 working through an ear 37.

A contact arm 38 is secured to the cover section 22 by the pivot pin 39 and this arm 15 is provided with a fixed contact point 40 and a movable contact point 41 mounted on a spring 42. The contact point 40 is adapted to be engaged by a contact point 43 on a kicking bar 44. This bar is formed with a 20 longitudinal slot 45 through which extends a guide pin 46. The bar is formed with an enlargement 47 adjacent one end which is adapted to engage a tripping screw 48 adjustable through an ear 49. A spring 50 25 retracts the kicking bar after each operation thereof.

A circuit making and breaking lever 51 having arms 52 and 53 is secured on the cover section 21 by a pivot stud 54 and is 30 swung in one direction by a spring 55. The arm 52 carries a contact point 56 mounted on a spring 57 and is further provided with a cam engaging enlargement 58. The arm 53 of the lever or interrupter 51 is formed 35 with a tooth 59 which engages a shoulder 60 formed on the kicking bar as shown.

A distributor 61 is secured to the upper end of the shaft 9 and is adapted to individually engage terminals 62 of the spark 40 plug wires and is also adapted to continuously engage a terminal 63. These terminals extend through and are supported by a non-conductive shell casing 64 which is secured to the housing or shell 14 as shown.

45 Referring now to the diagrammatic view, the operation of the system may be described as follows:

The lever or interrupter 51 is moved by the cam 25 traveling in the direction shown 50 by the arrow to engage the contact 56 with the contact screw 34 whereupon the current will flow from the magneto through the vibrator, primary winding and contacts 34, 55 56 to ground. The current flowing through the primary winding sets up induced current in the secondary winding which flows to the distributor 61, and through one of the wires to the respective spark plug. The contact screw 34 may be adjusted so as to cause it 60 to contact with the point 56 for the desired length of time. As the lever 51 is operated by the cam 25, its arm 53 moves the kicking bar longitudinally and carries its contact point 43 beyond the contact point 40 on the 65 contact arm 38. When the kicking bar has

been moved a predetermined distance, the tripping screw 48 engages the enlargement 47 thereon rotating the bar about its pivot pin 46 to disengage the bar from the lever arm 53 whereupon the bar is retracted by 70 the spring 50 causing a short contact of the contact point 43 with the contact point 40 whereupon the contact 41 is engaged momentarily with the contact screw 36 causing current to flow from the battery through the 75 primary winding and contacts 36, 41 to ground. Current flowing from the primary winding sets up an induced current in the secondary winding which flows to the distributor 61 and thence to one of the spark 80 plugs. It will be seen that with both the magneto switch and the battery switch closed a very rich spark will be produced. The tripping screw 48 may be adjusted to cause a proper release of the kicking bar 85 from the lever arm 53 and the tooth 59 on this arm prevents the lever swinging about its pivot pin to move the contact point 43 from the path of the contact point 40 when the bar is retracted. 90

From the foregoing description taken in connection with the accompanying drawings, it will be seen that I have provided a very simple and practical dual ignition system which may be operated on either the 95 magneto circuit or battery circuit or both and which will cause an accurate timing of the ignition in the various cylinders of a multiple cylinder engine.

While I have shown and described the 100 preferred embodiments of my invention, it will be clearly understood that I do not wish to be limited to this construction, but may make such changes as will fall within the scope and spirit of the invention as claimed. 105

What I claim is:—

1. A timer for ignition systems comprising a pivoted lever, positive means for moving the lever in one direction, spring means for actuating the lever in the other direction, a spring mounted contact point on one arm of said lever, an adjustable contact member adapted to be engaged by said contact point, a kicking bar movable in one direction by said lever and spring means for 110 retracting said kicking bar.

2. A timer for ignition systems comprising a cam, means for rotating said cam, a pivoted lever adapted to be moved in one direction by said cam, spring means for 120 moving the lever in the other direction, a contact point carried by said lever, a terminal adapted to be engaged by said contact point, a pivoted contact arm, a contact point carried by the said arm, a terminal adapted 125 to be engaged by said contact point and a slideable kicking bar operable in one direction by said lever, and a spring for retracting the kicking bar, the kicking bar being adapted to engage on its rearward movement the 130

contact arm to force its contact into engagement with the corresponding terminal.

3. In a timer for ignition systems, a shaft adapted to be driven by the engine, a cam 5 rotated by said shaft, a pivoted lever adapted to be engaged by said cam and moved in one direction to close a circuit, a kicking bar, means slidably mounting said kicking bar for longitudinal movement, said kicking bar 10 being moved in one direction by the pivoted lever, a tripping screw for disengaging the kicking bar from said lever, and spring means for retracting the kicking bar, said kicking bar being adapted on its rearward 15 movement to close a second circuit.

4. In an ignition system for internal combustion engines, a shaft driven by the engine, a cam, gearing connecting said cam with said shaft for rotational movement, a 20 pivoted lever adapted to be engaged by said cam and moved in one direction to close a circuit, a kicking bar adapted to be moved in one direction by said lever, means for releasing the kicking bar from the lever and 25 means for retracting the kicking bar when released from the lever to close a second cir-

cuit, and a distributer mounted on and actuated by said shaft.

5. In an ignition system for internal combustion engines, a shaft adapted to be driven by an engine, a cam, gearing connecting said cam with the shaft, a pivoted lever, a contact on said lever, an adjustable contact screw adapted to be engaged by said contact, a primary magneto circuit including said 30 adjusting screw, a pivoted contact arm, an adjustable contact screw adapted to be engaged by said contact arm, a primary battery circuit including said last mentioned adjusted screw, a kicking bar movable in one 35 direction by said lever, means for releasing the kicking bar from the lever, means for retracting the kicking bar when released from the lever to momentarily engage the contact arm with its contact screw, a secondary magneto circuit, a secondary battery 40 circuit, and a distributer in said secondary circuits, said distributer being connected to and operated by the shaft of the timer.

In testimony whereof I affix my signature. 50
